RADIATOR SIPHON

Axel A. Johnson, Holly, Mich.

Application December 24, 1947, Serial No. 793,633

2 Claims. (Cl. 222—204)

1

My invention relates to an improved device particularly useful in removing liquid cooling medium, e. g., water, from the radiators of internal combustion engines, as when it is desired to replace a part of the same with anti-freeze solutions. Ordinarily, this is accomplished by opening a small pet-cock which it is usually difficult to reach, and allowing the cooling liquid to drain from the radiator onto the ground. On cold days, this is a slow and uncomfortable operation when the hands are cold and the pet-cock is frozen or hard to release and there have been frequent scaldings of the service station attendants. Moreover, the draining of the water onto the surface of the service station area, creates a dangerous slippery situation underfoot, particularly in freezing weather. Also, in the use of the pet-cock, there is no accurate way to regulate the amount of cooling medium withdrawn, and since frequently in the winter season, the coolant only requires replacement of one or two quarts of anti-freeze, the release of an excessive amount of water from the radiator will require not only its replacement but replacement of an unnecessary added amount of expensive anti-freeze solution.

It is the object of my invention to eliminate the aforesaid difficulties by the use of a very simple and inexpensive device which will now be described, in connection with the accompanying drawings where:

Figure 1 is a perspective view;

Figure 2 is a sectional view showing the bulb and tube connection, and

Figure 3 is a view illustrating the device in Figure 1 operatively associated with an automobile radiator.

Referring to Figure 1, the invention comprises a preferably elliptical-shaped bulb 10 of any suitable compressible material, such as vulcanized natural rubber or synthetic rubber which will not be attacked by the cooling medium such as water and the usual anti-freeze compositions. The bulb 10 has a short, integral, tubular outlet portion 11 at one end, open to atmosphere, and at its other end has a similar tubular inlet portion 12 to which is connected a flexible tube 13 of similar rubber material and of substantial length. The end 14 of the tube 13 may be inserted within the tubular portion 12 and held therein by cementing or by vulcanization to assure permanent communication between the tube 13 and the bulb but preferably an inner coupling sleeve 15 of rigid material such as copper tubing or plastic is used,

as shown in Figure 2, to interconnect the end 14 and tubular portion 12, and to which sleeve the rubber may be cemented or vulcanized. The sleeve being disposed within both the inlet 12 and the tube a substantial distance, as shown, will prevent sharp bending of the tube at the point of connection with the bulb. The tubular portions 11 and 12 have walls of greater thickness than the wall of the tube 13 to provide relatively firm outlet and inlet portions on the elliptical-shaped bulb. A coil of wire 16 is wound about the end of the tube 13 adjacent the bulb, as shown, additionally to prevent sharp bending of the tube at its connection with the bulb and reinforce the connection, whereby the life of the device is substantially enlarged. The coil 16 extends from the butt-joint of the tube 13 with the outlet 12 to a point beyond the extent of the sleeve 15 within the tube.

At its opposite or free end, the tube 13 is provided with a resilient retaining member 17. This member 17 is slidably and frictionally carried on the tube so that the extent of the entrance of the open end of the tube into the radiator may be adjusted. The retaining member is formed of a single strand of resilient wire and has two diverging legs 18 which are centrally joined by the coil 19. The coil 19 frictionally receives the tube 13 in a manner to permit the member 17 to be adjusted thereon and without at any time impeding flow through the tube.

In use, the operator removes the radiator cap, and inserts the free end 21 of the tube 13 into the radiator and inserts the spring retaining member 17 into the upper end or filler neck 22 of the radiator, as shown in Figure 3. The resilient legs 18 are compressed for insertion and upon being released within the radiator neck these resilient legs expand and firmly engage the radiator neck to hold the device in position with the portion 23 of the tube 13 immersed in the coolant. Thereupon, the operator places his finger over the opening 24 of the atmosphere outlet 11 of bulb 10 and compresses the bulb. Upon releasing the bulb but still keeping the atmosphere outlet 11 closed, liquid will be withdrawn from the radiator through the tube 13 into the bulb 10 whereupon by removing the finger from the opening 24, the liquid will flow from the bulb through the outlet 11 in the desired amount. The amount of cooling liquid withdrawn may be generally estimated by the extent of the portion 23 disposed in the radiator, but preferably the flow from the bulb is collected in a vessel of known or marked capacity

so that, for example, 1 quart, 2 quarts, 3 quarts, etc. may be accurately withdrawn without waste or producing a slippery road condition.

I claim:

1. For use in draining coolant from radiators of internal combustion engines, a compressible bulb having an outlet to atmosphere, a flexible tube of substantial length connected to the bulb, and a spring retaining member slidably carried on said tube and adapted when the free end of the tube is inserted in a radiator to engage the interior wall of the radiator filler neck and retain the free end of the tube in draining position, whereby an operator placing his finger over the outlet to atmosphere and first compressing and then decompressing said bulb will draw liquid into the bulb and by removing his finger allow continuous flow of liquid from the bulb through the outlet in the desired amount, said retaining member being formed from a single strand of wire and having a pair of outwardly diverging spring legs and an intermediate coil slidably and frictionally receiving said tube without impeding the flow of liquid through the tube.

2. For use in draining coolant from radiators of internal combustion engines, a compressible bulb having an outlet to atmosphere, an inlet, a flexible tube of substantial length connected to said inlet, and a spring retaining member slidably carried on said tube and adapted when the free end of the tube is inserted in a radiator to engage the interior wall of the radiator filler neck and retain the free end of the tube in draining position, whereby an operator placing his finger over the outlet to atmosphere and first compressing and then decompressing said bulb will draw liquid into the bulb and by removing his finger

allow continuous flow of liquid from the bulb through the outlet in the desired amount, said inlet and said tube being connected by an inner coupling sleeve to which both the tube and the inlet are united, said retaining member being formed from a single strand of wire and having a pair of outwardly diverging spring legs and an intermediate coil slidably and frictionally receiving said tube without impeding the flow of liquid through the tube, and a coil of wire wound about the end of the tube adjacent the bulb to prevent sharp bending of the tube at its connection with the bulb and reinforce the connection.
